UNITED STATES PATENT OFFICE.

WILLIAM FREDERICK McMAHON, OF RIVERSIDE, CALIFORNIA.

PUMP PISTON.

Application filed March 4, 1927. Serial No. 172,689.

This invention relates to a novel construction for expanding the piston packing of a fluid pump piston, of a reciprocating pump, and has for an object to provide a piston adjusting means coacting with the fluid pump piston rod which will be watertight and will rotate the entire fluid pump piston when the said piston packing is adjusted by the rotating of the said piston rod adjusting means.

Another object is the novel construction and operation that not only provides a watertight means for adjusting the pressure of the piston packing, but with each adjustment of the piston packing, the angular position of the entire piston including the packing therein is shifted radially about its axis, so that each adjustment brings a different portion of the piston and piston packing adjacent any given surface of the cylinder, thus causing a uniform wear and perfect fit at all times in the cylinder in which the said piston reciprocates.

With these and other objects in view, the invention resides and consists in the construction and novel combination and arrangement of parts hereinafter more fully described, illustrated in the accompanying drawings, and pointed out in the claims here-to appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1 is a central longitudinal section through my improved piston construction.

Figure 2 is a transverse sectional view through the piston at "2-2", showing the general formation of the piston packing and the spiral jaw interengaging means for rotating the piston member and piston follower together.

Fig. 3 is a diagrammatic view of the spiral jaw interengaging means, showing the general engaging construction.

Referring in detail to the characters of reference marked upon the drawings 1 represents the crosshead, of a reciprocating pump, that connects the steam piston with the water pump piston 2.

It is into this crosshead 1, that I screw my novel piston rod 3 which comprises a solid rod 3 and a threaded sleeve 4, and a tube 5 which encases a portion of the solid rod 3.

By referring to Fig. 1, it will be noted the main members of the piston proper 2, namely the piston member 6 and the piston follower 7, are both connected directly to the solid rod 3 by threaded engagement and that the tube 5 serves only to rotate the piston proper 2. This said tube 5 has no tension or compression stress due to the reciprocating action of the piston 2 upon the fluid being pumped. This said feature is one of the main novel features of my improvement.

While this piston construction is substantially the same in the formation of the packing as my Patent Number 1,474,201, dated Nov. 13th 1923 and also substantially the same in the feature of rotating the entire piston to adjust the piston packing as described in my application Serial Number 101,969, dated Apr. 14, 1926, it should be noted that in the construction of this improvement the piston member 6 and the piston follower 7 both move in a longitudinal direction toward each other whereby the piston packing 8 is both compressed and expanded. In my Patent Number 1,474,201 and my patent application Serial Number 101,969 the piston member is held against longitudinal movement and the piston follower therein only moves in a longitudinal direction.

Heretofore the main drawback to a positive mechanically adjusted piston was that they were not watertight. To make an absolute watertight piston I prevent the fluid from entering into the space between the solid rod 3 and the tube 5 by incorporating a series of fine threads 9 and 10 which prevents the fluid being pumped from entering the said space.

Sleeve 4 is a tube having threads on the outside diameter and on the inside diameter, the said threads on the inside diameter are provided for threaded engagement with the solid rod 3. This sleeve 4 is provided to allow the tube 5 to be assembled on solid rod 3 and to connect the solid rod 3 with the crosshead 1. A taper pin 11 holds the sleeve 4 from rotating when the solid rod 3 is being assembled with the crosshead 1.

Solid rod 3 is basicly the piston rod of

the pump, the entire strain due to the pumping of the fluid by the piston coming entirely upon this said rod 3, (as before said there is no strain or stress on the tube 5). Solid 5 rod 3 serves to connect the piston member 6 and the piston follower 7 in direct relation with each other. The rod 3 is held stationary from rotating by locknut 12 located on the crosshead portion of said rod 3 and 10 on the piston end portion I have provided two series of threads 9 and 10, which are left and right handed respectively. As the piston member 6 and the piston follower 7 have threaded engagement with the 15 threads 9 and 10 respectively it will readily be seen that when the entire piston is rotated the piston member and follower will move in a longitudinal direction toward each other.

Tube or sleeve 5 is a tubular rod having 20 threaded engagement 13 with the piston member 6. The main function of this rod 5 is to rotate the entire piston proper 2. On the cross head 1 portion of this tube 5 a locknut may be provided if desired. This 25 locknut is designated in the Fig. 1, by number 14.

Piston member 6 is a cylindrical disc with a conical face 15 and a central outwardly disposed hub 16 that contains the spiral jaw 30 clutch 17 which is cast integral with the piston member 6. This spiral jaw clutch 17 provides the interengaging means between the piston member 6 and the piston follower 7. It should be noted that a square jaw 35 clutch or a key could serve equally as well as the said interengaging means. On the other end portion of this central outwardly disposed hub 16 there is a pipe thread 13 for threaded engagement with the tube 5.

40 The piston follower 7 is a cylindrical disc with a conical face 15 similar to that of the piston member 6. I have provided these conical faces 15 to actuate the flexible packing 8 that is located between them. It is 45 noted that when the piston member 6 and the piston follower 7 are moved in a longitudinal direction toward each other the said flexible packing 8 will be both compressed and expanded. This flexible packing 8 may 50 be made of any pliable material but is preferably made of a rubber composition. It is tubular in formation with a symmetrical conical face 15 on the both ends of same. The outer diameter 19 will bear on the adjacent surface of the water pump liner in 55 which the entire piston reciprocates and the inner diameter 20 will be supported on the hub 16 of the piston member 6 and the piston follower 7.

60 In the central hub 21 of the piston follower 7 is a series of threads for engagement with the threaded portion 10 of the solid rod 3. In the central hub 16 of the piston member is a similar series of threads, but of an opposite hand, for threaded engage-

ment with the threaded portion 9 of the said solid rod 3, so that it will be seen that by holding the solid rod 3 stationary from rotating and against longitudinal movement and by rotating the both members 6 and 7 70 of the piston simultaneously in cooperation with the threaded portions 9 and 10 of the solid rod 3, they being of different hands, the said rotation will cause the both members 6 and 7 to move in a longitudinal direction toward each other. 75

I wish to call attention to the fact that the sleeve 4 may be eliminated if the crosshead is provided with threads to suit the threaded end portion 22 of the solid rod 3. 80

Also note that I have provided an interengaging means on the piston follower 7 that will coact with the interengaging means 17 of the piston member 6. This interengaging means will be cast integral with the piston follower 7 and will be of the well known spiral jaw clutch 17 formation. This interengaging means 17 permits the both members 6 and 7 of the piston to be rotated simultaneously when the tube 5 is revolved. 85

From the above description it will be observed that I have provided a novel construction, whereby when the tube 5 is rotated the both members 6 and 7 of the piston proper and the packing 8 will be rotated and at 95 the same time the piston member 6 and the piston follower 7 will both be moved in a longitudinal direction toward each other thereby compressing and expanding the piston packing 8. 100

What I claim and desire to secure by Letters Patent is:

1. In a reciprocating pump, a pump piston comprising two members both of which are longitudinally adjustable relatively to each other, a pliable packing between said members adapted to be shifted upon contacting the relation of said members, a tubular rod connected to one of the said members, a stationary means within the tubular rod having threaded connection with both of the said members, and interengaging means between said members to cause them to rotate together whereby rotation of said rod will change the relative positions of said members. 110

2. In a reciprocating pump, a pump piston comprising two members both of which are longitudinally adjustable relative to each other, a pliable packing between said members, a tubular rod having connection with said members and adapted to be rotated to impart a rotating movement to said members, and means extending within the said tubular rod having threaded connection with the both said members to shift said members by rotation of said members whereby the pliable packing is adjusted by turning movement of said members. 120

3. In a pump piston, two cylindrical discs

adapted to be moved in a longitudinal direction toward each other, each said cylindrical disc having a conical surface that opposes the other, a packing between said conical surfaces and shifted by change in the relative positions of said conical surfaces, a stationary member having screw thread connection with the two said cylindrical discs, a coacting means carried by the two said cylindrical discs to cause them to rotate simultaneously, a tubular rod having connection with the said discs and adapted to be rotated to impart a rotating movement to said discs whereby rotation of said discs will change the relative positions of said discs and actuate the said packing.

4. In a reciprocating pump, a pump piston comprising two coniform members adapted to be longitudinally moved toward each other, a packing between said members and adapted to be shifted by change in the relative positions of said coniform members, a stationary rod having screw thread connection with both said coniform members, and means for turning the both said coniform members simultaneously to adjust their positions relative to each other whereby the said packing is actuated.

5. In a reciprocating pump, a pump piston comprising two members adapted for longitudinal movement toward each other, both said members having opposed conical surfaces, a packing between said conical surfaces and shifted by change in the relative positions of said conical surfaces, interengaging guide means carried by said members arranged to prevent relative turning movement while permitting relative longitudinal movement, a stationary rod connected to the two said members by a screw thread for imparting longitudinal movement thereto by rotation of said two members, and a rotatable rod mounted on said stationary rod and connected to the said members to rotate the same by the rotation of said rod.

6. In a pump, a plunger rod held against rotation upon the plunger rod coupling, a sleeve disposed about the plunger rod, a head mounted upon the sleeve and also threadedly mounted upon the plunger rod, a second head threadedly mounted upon the plunger rod, means for holding the heads against relative rotation, and an expansible packing disposed between the heads whereby rotation of the sleeve said heads may be caused to rotate together, causing the both heads to move toward or away from each

other to expand the packing or to permit it to contract.

7. In a pump having a plunger rod coupling, a plunger rod secured against rotation relatively thereto, a sleeve disposed about the plunger rod having one end bearing against the plunger rod coupling, a head rigidly mounted upon the sleeve and also threadedly mounted upon the plunger rod, a second head threadedly mounted on the outer end of the plunger rod, means holding the heads against relative rotation, a packing disposed between the heads and adapted to be expanded when the sleeve is rotated, causing the heads to rotate and causing the both heads to move toward each other, and means providing an abutment against which the end of the sleeve will abut at assembly.

8. A pump plunger comprising a piston rod, a sleeve disposed about the piston rod, a head secured to the sleeve and having threaded connection with the piston rod, a second head threadedly mounted upon the piston rod, means for locking said heads against relative rotation, a packing disposed between the heads.

9. In a pump having a piston rod coupling, a piston rod secured against rotation relatively thereto, a sleeve disposed about the piston rod, a first head secured to the sleeve and threadedly mounted upon the piston rod, a second head threadedly mounted upon the piston rod, means for locking said heads against relative rotation, a packing disposed between the heads, and means providing a shoulder on the other end of the piston rod for securing the piston rod to the piston rod coupling.

10. A pump plunger comprising a piston rod, a sleeve disposed about the piston rod, two heads each threadedly mounted on one end of the piston rod in a right and left hand threaded formation respectively, one of the heads secured to the sleeve, means for locking said heads against relative rotation, a packing disposed between the heads, and means for turning the sleeve whereby upon rotation of the both heads and sleeve the both heads will be adjusted toward or away from each other to expand the packing or to permit it to contract when the piston rod is held stationary.

Signed at Riverside, in the county of Riverside, and State of California, this 28th day of February, 1927.

WILLIAM FREDERICK MoMAHON.
